UNITED STATES PATENT OFFICE.

WILLIAM C. RISERIDGER AND MILTON W. RISERIDGER, OF CLEVELAND, OHIO, AS
SIGNORS OF ONE-THIRD TO E. F. JOHNSON, OF CLEVELAND, OHIO.

FILLET FOR PATTERNS.

972,473.

Specification of Letters Patent. Patented Oct. 11, 1910.

Application filed April 8, 1909. Serial No. 488,688.

To all whom it may concern:

Be it known that we, WILLIAM C. RISERIDGER and MILTON W. RISERIDGER, citizens of the United States, residing at Cleveland, 5 in the county of Cuyahoga and State of Ohio, have invented certain new and useful Improvements in Fillets for Patterns, of which the following is a specification.

This invention relates to improvements in 10 fillets for patterns, especially wood patterns, and the improvement consists in making a flexible fillet of vegetable matter, such as paper or pulp, and which involves a new mode of construction and develops new 15 properties in the article made, and which in practice shows its superiority to not only consist in greater cheapness and durability but also in a more efficient action, both in application and use as compared with fillets 20 made and used heretofore, all substantially as hereinafter described and more particularly pointed out in the claims.

In the accompanying drawings, Figure 1 is a sectional view of a pattern having a 25 compound curve and illustrating the application of our improved fillet thereto, and Figs. 2 and 3 are sectional views of the same pattern showing fillets in plain elevation and cross section in different corners 30 thereof. Fig. 4 is a perspective view of a portion of the laminated product from which our fillet is formed. Fig. 5 is a perspective view of a portion of a fillet in one of its stages of manufacture, and Fig. 6 is 35 a cross section of the fillet in a further stage of development. Fig. 7 is a perspective view of a short strip of our improved fillet finished and as sold to the trade.

Heretofore, fillets for patterns have been 40 made either of wood, leather, lead or rubber and although each one named may have distinct advantages one over the other, each possesses certain disadvantages which limit their use. Thus, wooden fillets are not sufficiently flexible or pliable to conform to 45 curved surfaces nor to different angles, therefore requiring different shapes and sizes of fillets or special labor to fit the same in place. The edges of a fillet are necessarily thin, and these thin edges when of 50 wood will warp when glue is applied to fasten the same to the pattern.

Leather fillets contain oil or animal fat and will not always hold when glued to 55 place especially when subjected to heat from

the sand during molding operations, and furthermore, leather does not properly retain an alcohol shellac finish which is found necessary to apply to all patterns for their protection and to further facilitate the withdrawing of the mold from the sand. Neither can leather be smoothly sandpapered to make a satisfactory finish. Leather fillets also require special forming tools to apply them to patterns.

Rubber fillets fray and produce a rough job when the pattern and the fillets are sandpapered, and again, such fillets will not take and hold shellac with any degree of practicability. Rubber fillets are affected by heat and will loosen from the pattern if glued thereto. When softened by heat, sand will adhere to a rubber fillet and destroy or make a rough mold. The inherent spring of rubber fillets also tends to loosen them from the 75 patterns, especially if the fillet is stretched or compressed out of its natural shape.

Lead fillets can not be glued, so are hammered and nailed in place which makes an uneven job, and the finishing shellac will not 80 adhere to its surface thus exposing the lead to hot sand which leads to rough work and a poor mold. Lead is heavy and impracticable in many instances, particularly for small or light patterns.

Now referring to our invention, we have discovered that a fillet A made of paper, strawboard, pulp, or other vegetable or like fibrous material not only has all the good features of the different kinds of fillets heretofore used, but in addition has several advantages over each of them without their disadvantages as enumerated, and in constructing fillet A of this material we prefer to build it up in laminations by superimposing layer upon layer of fine sheets a, see Fig. 4, and compressing them together to a compact mass to give a tough but flexible or pliable body which may be bent to curves without breaking and which is susceptible to moisture to permit a greater degree of flexibility in case of need. When dry, a fillet made and formed like ours is readily sandpapered to any degree to make fine tapering edges adapted to merge with the pattern without a break or flaw, and being of vegetable matter, it will take and hold the shellac which is always applied to patterns to protect and smoothly finish them. Our fillet is readily glued to place and practi-

cally becomes an integral part of a wood pattern because of its peculiar affinity to that material when attached thereto by glue, and when shellacked will not warp or loosen 5 during exposure to the atmosphere or to the warm or hot sand in foundry operations. A paper or like fillet will absorb the glue and the moisture from the glue makes it even more pliable than naturally and therefore 10 can be used to great advantage on either straight or curved surfaces without warping. In thus applying the fillet, no tool is required, the pattern maker simply using his fingers and hands, and because of the peculiarities 15 of such a fillet, a fillet of any given angle or shape in cross section may be caused to conform to a corner of relatively different angles to snugly fit and fill the same. Thus, a fillet having two flat or 20 substantially flat faces —2— and —3—, disposed at right angles or ninety degrees, see Fig. 7, may be compressed or spread to an acute or more obtuse angle as desired. It will be understood that fillet A as an article 25 of manufacture and sale is of a fixed shape preferably as shown in Fig. 7, and although flexible to a certain degree is still stiff and firm enough to retain this shape for convenience in handling. In the manufacture of 30 this article, a laminated straw-board or like material B is used, see Fig. 4, which is then cut to the triangular shape C seen in Fig. 5. The next step is to shape this flat sided triangular strip C into the crescent shape D, 35 shown in Fig. 6, and finally to form the finished article shown in Fig. 7, with two right angled flat faces —2— and —3—, and a curved face —4—. By this mode of construction, sharp straight edges —5— are obtained 40 and although of paper or pulp said edges are not ragged or will not break down, one reason being that each superimposed sheet *a* contributes to the strengthening of the next and being thin, each sheet is necessarily 45 sharp the full length of the strip at either edge thereof. When the fillet is glued into place upon pattern P, the same may be sandpapered without leaving ragged edges; in fact a laminated fillet of paper lends 50 itself admirably to the making of a fine smooth surface without ridge or offset at the joints, and our fillet may be rounded or

sandpapered down to any angle or shape the same as wood.

Briefly recapitulating, our improved fillet 55 has these advantages; it is by nature a non-conductor of heat and therefore retains its adhesion perfectly when applied to the pattern regardless of many conditions to which the pattern may be exposed; it will absorb 60 sufficient glue when applied thereto to strongly fortify it in body and thereby assure its adhesiveness to the pattern to become an integral part of the pattern more completely than otherwise; it will flex or 65 bend within limits when dry to conform to various shaped and forms of patterns and which flexibility may be further enhanced when dampened by the application of water or steam or by the mere use of the glue 70 which adheres it to the pattern; its relative angles though set to any given degree will change and adapt themselves to corners of different angular degrees; it will take a fine finish without fraying at the edges when 75 sandpapered, and it will take and retain the protecting coat of shellac which is necessary to the fillet and the pattern for molding purposes.

What we claim is:—

1. A fillet consisting of numerous sheets of fibrous material cemented together in block form and the edges of the fillet chamfered at an inclination the full depth of the fillet from its middle to its opposite edges. 80 85

2. A fillet consisting of numerous sheets of fibrous material cemented one upon the other to the desired thickness in block form, and the edges of said sheets chamfered off at an inclination to the plane of said sheets 90 from the middle at one side to the edges of the other side and adapted to be bent from its middle to approximately crescent shape, whereby all the layers in the fillet are bent correspondingly and the integrity of the 95 structure is maintained.

In testimony whereof we affix our signatures in presence of two witnesses.

WILLIAM C. RISBRIDGER.
MILTON W. RISBRIDGER.
